RECEPTACLE-MOUNTED ORDER INDICATOR
FOR DAIRY PRODUCTS AND THE LIKE

Benjamin Ginsberg, Philadelphia, Pa.

Application January 26, 1955, Serial No. 34,202

Term of patent 14 years

(Cl. D52—1)

Fig. 4.

Fig. 2.

Fig. 3.

Fig. 1.

Figure 1 is a perspective view of a receptacle-mounted order indicator for dairy products and the like showing my new design;

The bottle carrier shown in broken lines is for illustrative purposes only.

I claim:

The ornamental design for a receptacle-mounted order indicator for dairy products and the like, as shown and described.
